POCKETED BAG FOR SMALL ARTICLES

Irene C. Huch, St. Paul, Minn.

Application March 10, 1952, Serial No. 18,838

Term of patent 14 years

(Cl. D58—2)

To all whom it may concern:

Be it known that I, Irene C. Huch, a citizen of the United States, residing at St. Paul, county of Ramsey, and State of Minnesota, have invented a new, original, and ornamental Design for Pocketed Bag for Small Articles, of which the following is a specification, reference being had to the accompanying drawing, forming a part hereof.

The figure is a perspective view of a pocketed bag for small articles showing my new design.

The rear view of the bag is the same as the front view shown.

I claim:

The ornamental design for a pocketed bag for small articles, as shown and described.

IRENE C. HUCH.
